UNITED STATES PATENT OFFICE

WILLARD A. SCHWARTZ, OF LOS ANGELES, CALIFORNIA

PAPER GRASP FOR PAPER CUTTING AND FOLDING MACHINES

Application filed September 8, 1932. Serial No. 632,134.

This invention relates to a mechanism for grasping sheets of paper in paper cutting and folding machines and particularly pertains to a paper grasping appliance for use on one of the revolving paper feed cylinders of a newspaper cutting and folding machine for holding one or more sheets of paper in place on the cylinder during the cutting operation and preparatory to feeding the paper from the cylinder to a folding device.

An object of the invention is to provide a paper grasp of the above character which is so formed and operated as to obviate perforation and consequent mutilation of the paper sheet as occurs in the types of paper grabs now generally in use in machines for folding news prints and the like.

Another object is to provide a paper grasp which includes an arrangement of clamps carried on a revoluble paper conveying cylinder and adapted to be moved in and out of clamping engagement with the marginal portions of sheets of paper on the cylinder, and to provide mechanism for actuating the clamps and to time their engagement with and disengagement from the paper sheets at predetermined points in the peripheral travel of the cylinder.

Another object is to provide a construction whereby the clamps are adapted to operate with relation to either one layer of paper or a plurality of layers carried on the paper conveying cylinder, and to provide a means in such construction for enabling ready manual adjustment of the clamps to accommodate them to various operating conditions.

Another object is to provide a paper clamping mechanism of the above character which is simple in construction, efficient in its operation, and adapted to be actuated at high speed.

With the foregoing objects in view together with such other objects and advantages as may subsequently appear, the invention resides in the parts and in the combination, construction and arrangement of parts herein-

after described and claimed, and illustrated by way of example in the accompanying drawings in which:

Fig. 1 is a view in longitudinal section of a paper conveying cylinder, showing the invention as applied; parts being broken away, and portions being shown in elevation;

Fig. 2 is a view in vertical section and elevation as seen on the line 2—2 of Fig. 1 in the direction indicated by the arrows;

Fig. 3 is a detail in horizontal section taken on the line 3—3 of Fig. 1;

Fig. 3^a is a detail in cross section viewed on the line 3^a—3^a of Fig. 3 in the direction indicated by the arrow;

Fig. 4 is a detail in section taken on line 4—4 of Fig. 2 illustrating the cam contour;

Figs. 5, 6, 7 and 8 are diagrams in section and elevation illustrating the mode of operation of the invention; Fig. 5 showing the parts as disposed in their normal position in readiness for operation; Fig. 6 showing the clamp as advanced in readiness to be actuated to engage the paper; Fig. 7 showing the clamp as disposed in engagement with the paper; and Fig. 8 showing the parts in an intermediate position with the clamp as initially freed from the paper;

Fig. 9 is a detail plan view of the paper clamp as seen on the line 9—9 of Fig. 7;

Fig. 10 is a detail in cross section taken on the line 10—10 of Fig. 9; and

Fig. 11 is a view in vertical section taken on the line 11—11 of Fig. 8, showing the manually operated clamp adjustment.

Referring to the drawings more specifically, A indicates generally one of the revoluble paper conveying cylinders of a newspaper cutting and folding machine, which cylinder is mounted on a shaft B supported in frame members C and D and which shaft is driven in the usual manner to effect rotation of the cylinder A.

The cylinder A embodies a peripheral wall portion 14 around which one or more layers

of sheets of paper are adapted to be passed and includes end walls 15 and 16 fitted with hubs 17 and 18 affixed to the shaft B. The wall 14 is formed adjacent each end of the cylinder with diametrically opposed pairs of slots, indicated at 19, in each of which slots is mounted a slide block 20 adapted to be shifted longitudinally of the cylinder; the slide blocks being formed with longitudinal channels 21 and 22 on opposite sides thereof, as shown in Fig. 10, which channels are engaged by keys 23 and 24 demountably supported in longitudinal channels 25 and 26 formed in the side walls of the slots 19. The keys 23 and 24 are inserted into the channels 21-25 and 22-26 through openings 27 and 28 in the end walls of the cylinder, as shown in Fig. 9.

Mounted on each of the slide blocks is a clamp 30 one end of which is mounted on a pivot pin 31 carried on the outer end of the slide block so that the clamp may swing inwardly and outwardly relative to the outer periphery of the cylinder; the several clamps being arranged with their outer free ends extending inwardly from the ends of the cylinder so as to project toward the margins of a sheet or sheets of paper F disposed on the cylinder. Pivotally secured at 32 to the under side of each of the clamps 30 is a rod 33 which passes through an opening 34 in the slide block 20 and leads interiorly of the cylinder, and connecting with each of the rods 33 is a pair of spaced arms 34 and 35; each arm 34 being connected by a pivot pin 36 to the rod 33 intermediate the ends of the latter and each arm 35 being connected by a pivot pin 37 to the end of the rod 33 opposite the pivot 32 in spaced relation to the pivot 36.

The arms 34 extend through and are slidably supported for longitudinal and pivotal movement in openings 38 in the end walls of the cylinder, and carried on the outer ends of the arms 34 are rollers 39 arranged to traverse the surfaces of fixed cams 40 carried by the frames C and D. The arms 35 extend through slots 41 in the cylinder end walls, and fitted on the outer ends of the arms 35 are rollers 42 arranged to traverse cam grooves 43 formed on plates E fixed on the frames C and D. Each arm 35 is fitted intermediate its ends with a pivot pin 44 the ends of which pins protrude from opposite sides of the arms 35 and extend into elongated slots 45 in slide blocks 46 carried by guides 47 on the inner faces of the cylinder end walls, as shown in Fig. 3. A pair of springs 48 and 49 carried by each of the slide blocks 46 bear on opposite edges of the arms 35 diametrically opposite the axes of the pins 44 so to yieldably oppose movement of the pins 44 longitudinally of the slots 45 in either direction.

The slide blocks 46 are affixed on stems 50

extending radially of the cylinder along the inner sides of the end walls of the latter; the outer ends of which stems are formed with screw threads 51 screwed into engagement with turnable sleeves 52 extending through the peripheral wall 14 of the cylinder. The sleeves are held against longitudinal movement by end flanges 53 countersunk in the outer face of the wall 14 and collars 54 screwed on the sleeves 52 to slidably bear against the inner face of the wall 14. The outer ends of the sleeves 52 are formed with straight sided sockets 55 for the reception of a tool whereby the sleeves may be rotated to effect longitudinal adjustment of the stems 50.

Connecting with the rods 33 intermediate the pivotal connections thereof with the clamps 30 and arms 34 are springs 56 attached to the cylinder end walls, and which springs exert a pull on the arms 33 to normally maintain the slide blocks 20 in their retracted positions; the springs 56 opposing movement of the rods 33 under action of the arms 34 and cams 40.

Connecting with the arms 35 adjacent the pivots 37 are springs 57 which extend and are secured to the inner face of the cylinder wall 14, which springs yieldably oppose movement of the arms 35 in one direction under the action of the cam 43 and serve to maintain the rollers 42 in contact with the inner wall of the cam groove 43 and thereby act to prevent hammering of the rollers on the cam. The action of the springs 57 is such as not to affect the springs 48, in other words, the springs 48 are of such stiffness and tension as to oppose movement of the arms 35 and pivot pins 44 under the urge of the springs 57.

The cylinder A is formed with hand holes, (not shown) in the usual manner to afford access to the interior thereof for purposes of assemblage of the parts therein.

The cams 40 are each provided with a hump 58 arranged to act on the arms 34 as the cylinder A revolves at a predetermined point in the peripheral travel of the cylinder, to shift the arms longitudinally and thereby effect lateral movement of the rods 33 in opposition to the springs 56 and to advance the slide blocks 20, and each of the cam grooves 43 is contoured, as shown in Fig. 2, with a concentric portion *a* extending approximately one-half the length of the groove and with another concentric portion *b* of larger radius than the portion *a* extending approximately the other half of the length of the groove, which concentric portions *a* and *b* are connected by inclined portions *c* and *d* whereby on rotation of the cylinder the rollers 42 in traversing the grooves 43 will follow said contours and thereby rock the levers 35 as the rollers traverse the inclined portions *c*

and *d* of the grooves, as will presently be described.

In the operation of the invention, the cylinder *A* is revolved and a strip of a layer 5 or layers of paper is fed to the periphery thereof in the usual manner; the strip being fed to the peripheral portion of the roller at a point where the clamps 30 are open and retracted in a normal position, as shown in 10 Fig. 5, in which position the clamps are maintained while the rollers 42 on the arms 35 are traversing the concentric length *a* of the cam grooves 43, and during which time rollers 39 and arms 34 are traversing the dwell 15 portion of the cam 40 on opposite sides of the hump 58. The strip *F* is of such width that the edges thereof adjacent the point of meeting of the strip with the periphery of the cylinder will lie close to but spaced from the 20 open aligned pair of the clamps 30, as shown in Fig. 5.

The first operation is to cause the aligned open pair of clamps 30 on one side of the cylinder to advance over opposed marginal 25 portions of the strip of paper, as shown in Fig. 6. This is accomplished by the action of the humps 58 on the cams 40 which, as the cylinder *A* revolves, causes the arms 34, rods 33 and slide blocks 20 carrying the 30 clamps 30 to advance to the position shown in Fig. 6 in opposition to the springs 56. Immediately after the slide blocks 20 with their 35 associated clamps 30 being disposed in their advanced position the rollers 42 on the arms 35 ride upwardly in the inclined portions *c* of the cam grooves 43 thereby rocking the levers 35 so as to exert a downward pull on the rods 33 thereby moving the clamps 30 into engagement with the strip of paper *F*, 40 as shown in Fig. 7; the clamps being maintained in clamping engagement with the strip throughout substantially a one-half revolution of the cylinder *A* by reason of the rollers 42 on the levers 35 then traversing the concentric portions *b* of the cam grooves 43.

Shortly after the clamps 30 have been caused to engage the strip the rollers 39 on the arms 34 clear the humps 58 so as to permit the springs 56 to exert a pull on the rods 33 50 tending to retract the slide blocks 20. However, since the clamps 30 are then engaged with the marginal portions of the strip *F*, the slide blocks 20 will move only such distance under the urge of the springs 56 as will take up any slack transversely of the strip *F*. The springs 56 will thus serve to stretch and hold the strip *F* flat on the periphery of the cylinder. 55

When the cylinder has rotated to a point 60 where the rollers 42 on the arms 35, just referred to, pass from the sections *b* of the cam grooves downwardly through the inclined portions *d* the clamps 30 will, on the rollers 42 initially moving inwardly on the inclined 65 portions *d*, effect outward movement of the

clamps 30 sufficiently to relieve their grip on the strip *F* whereupon the springs 56 will retract the rods 33 and the slide blocks 20 with their associated clamps 30 and restore the arms 34 in position to be again actuated by 70 the humps 58 on the next operation. The parts will then be disposed as shown in Fig. 8. On the rollers 42 entering the portions *a* of the cam grooves 43, the clamps 30 will be fully opened and the parts restored to their 75 normal position, as shown in Fig. 5, in readiness for another operation.

The foregoing description of the operation has been confined to that of an aligned pair of the clamps on one side of the cylinder, but obviously a corresponding operation will be effected by the other pair of aligned clamps on the opposite side of the cylinder excepting that the operations will be alternated so that when one pair of the clamps is actuated to release the strip the other pair will be operated to engage the strip. The portion of the strip then surrounding one-half the perimeter of the cylinder is then severed and delivered to the folding mechanism in the usual manner, 80 and not necessary to be here shown since such cutting and folding mechanism constitutes no part of the present invention.

In even of variation of thickness of the strip *F* such will be compensated for by reason of the provision of the floating fulcrums or pivot pins 44 of the arms 35, since the springs 48 and 49 will yield to permit the pivot pins 44 to shift to whatever position may be necessary according to the limit of inward movement of the clamps 30. The device is thus adapted to automatically accommodate itself to clamping different thicknesses of paper on the cylinder within limits, but where it is necessary to adapt the clamps to operate on a more or less thickness of the strip they are then adjusted manually through the medium of the sleeves 52 to shift the positions of the pivot pins of the levers 35 as before described. 95

While I have shown and described a specific embodiment of the invention, I do not limit myself to the exact details of construction and arrangement shown, but may employ such changes and modifications in the parts and their arrangements, as occasion may require, coming within the meaning and scope of the appended claims.

I claim:

1. In a paper cutting and folding machine, a revoluble paper conveying cylinder, diametrically opposed pairs of paper clamps on the periphery of said cylinder arranged with the clamps of each pair disposed adjacent the ends of the cylinder and opening toward each other, means for actuating said clamps to alternately engage and disengage opposed marginal portions of sheets of paper disposed on said cylinder, and spring means for exerting a pull on said clamps when engaged with 100

120

125

130

the paper to effect stretching thereof between opposed clamps.

2. In a paper cutting and folding machine, a revolute cylinder, two pairs of paper clamps on the periphery of said cylinder, the clamps of each pair being spaced apart and opening toward each other and the pairs of clamps being spaced apart circumferentially of the cylinder, slide blocks carrying said clamps movable longitudinally of said cylinder, means for reciprocating said blocks, and means for opening and closing said clamps.

3. In a paper cutting and folding machine, a revolute cylinder, a plurality of slide blocks on the periphery of said cylinder adjacent each end thereof, cam controlled means for advancing said blocks longitudinally of said cylinder, spring means for retracting said blocks, paper clamps carried by said blocks, and cam operated means for opening and closing said clamps.

4. In a paper cutting and folding machine, a revolute cylinder, a plurality of paper clamps carried by said cylinder, rocker arms connected to said clamps, cam means for actuating said rocker arms to open and close said clamps, and means for automatically shifting said clamps longitudinally of said cylinder in parallel relation to the periphery thereof.

5. In a paper cutting and folding machine, a revolute cylinder, a plurality of paper clamps carried by said cylinder, rocker arms connected to said clamps, cam means for actuating said rocker arms to open and close said clamps, means for automatically shifting said clamps longitudinally of said cylinder in parallel relation to the periphery thereof, and floating pivot pins on which said arms are fulcrumed.

6. In a paper cutting and folding machine, a revolute cylinder, a plurality of paper clamps carried by said cylinder, rocker arms connected to said clamps, cam means for actuating said rocker arms to open and close said clamps, means for shifting said clamps longitudinally of said cylinder, floating pivot pins on which said arms are fulcrumed, and tension means for yieldably opposing movement of said pivot pins.

7. In a paper cutting and folding machine, a revolute cylinder, a series of paper clamps carried by said cylinder, positive means for advancing said clamps longitudinally of said cylinder, means for opening and closing said clamps when in their advanced position, and spring means for retracting said clamps longitudinally of said cylinder.

8. In a paper cutting and folding machine, a revolute cylinder, a series of pivoted paper clamps carried on the peripheral wall of said cylinder, rocker arms connected to said clamps, pivot pins supporting said arms, cam means for actuating said arms, yieldable sup-

ports for said pivot pins, and means for adjusting the positions of said supports.

9. In a paper cutting and folding machine, a revolute cylinder, a series of slide blocks carried on the peripheral wall of said cylinder, paper clamps pivoted on said blocks, rods connected to said clamps, cam means for reciprocating said rods longitudinally, cam means for shifting said rods laterally in one direction to advance said slide blocks, and springs connected to said rods for shifting said rods laterally to retract said slide blocks.
